UNITED STATES PATENT OFFICE.

JAMES SHEEAN, OF CAMDEN, NEW JERSEY.

NOTEBOOK-HOLDER.

1,381,757.

Specification of Letters Patent. Patented June 14, 1921.

Application filed February 5, 1920. Serial No. 356,518.

To all whom it may concern:

Be it known that JAMES SHEEAN, a citizen of the United States of America, residing at Camden, in the county of Camden and 5 State of New Jersey, has invented new and useful Improvements in Notebook-Holders, of which the following is a specification.

The object of the invention is to provide a note-book holder and line indicator 10 adapted for use by copyists particularly in connection with a typewriting machine, but also designed for use as a means of holding a copy-book or loose sheets as a tablet in taking notes or preparing manu- 15 script, and in that connection being suitable for arrangement flat on a desk or to be held on the lap or in the hand; and with these objects in view the invention consists in a construction and combination of parts 20 of which a preferred embodiment is shown in the accompanying drawing, wherein:

Figure 1 is a perspective view of the holder set up for use in holding a copy-book in a substantially upright position.

Fig. 2 is a side view of the same.

Figs. 3 and 4 are sectional views on the planes indicated respectively by the lines 3—3 and 4—4 of Fig. 1.

Fig. 5 is an edge view of the device 30 folded for use on the desk or on the lap of the operator.

The device consists essentially of a base or board 10 provided with a folding easel support 11 of wire or rod pivotally connected with the base or board at 12 and 35 adapted to be disposed as indicated in Figs. 1 and 2 at an angle to the plane of the board to support the latter in a substantially upright position, the outward movement of the frame constituting the easel 40 support or brace being limited by a flexible connection 13 consisting of a chain, tape or any equivalent thereof. The easel frame or base preferably comprises the side arms

45 14 and the transverse connecting bar 15, while the pivotal connection between said arms and the base or board 10 is provided by inturning the extremities of said arms to fit in sockets in the edges of the base or 50 board, so that when the brace is folded as indicated in Fig. 5 the side arms are adapted to lie substantially in the plane of the base or board. At its lower end said base in addition to the forwardly projecting 55 ledge 16 is provided with depending resilient knobs or cushions 17 of rubber or the

like forming buttons to bear upon the surface of a desk or the like to avoid scratching the same and at the same time prevent the structure from moving or sliding to 60 such an extent as to be objectionable, and when the easel brace 11 is folded the bottom cross bar 15 thereof snaps behind said buttons as indicated in Fig. 5, to lock said frame in the plane of the base or board to 65 adapt the device to be arranged flat upon the surface of the desk or to be held on the lap of the operator in taking notes.

Secured to the base or board near its upper edge is a transversely extending 70 clamping tongue 18 designed to engage the upper edge of the copy-book or a tablet or sheets of paper arranged upon the surface of the base while extending parallel with the left-hand edge of the base or board 75 is a gage bar or rib 19 against which the adjacent edge of the book or of sheets of paper arranged on the surface of the base may be fitted to dispose the same in accurate parallelism with the base. Also 80 mounted slidably upon the base preferably at its left-hand edge is a carrier block 20 having front and rear guide arms 21 and 22 of which the former bears and rides upon the guide bar or rib 19 while the 85 latter is provided with a terminal hook 23 for engaging and traversing a guide rib 24 projected from the rear surface of the base.

The carrier block is also provided with an indicator arm 25 preferably of spring metal 90 or similar material designed to extend in a direction exactly perpendicular to the guide rib 19 and bear upon the surface of the notebook or sheet of paper arranged upon the base and designed for movement from time 95 to time to indicate the successive lines of the copy for the convenience of the operator.

To move the indicator arm from time to time without tending to disturb the arrangement of the copybook or sheet on the base the 100 carrier block may be grasped and deflected either rearwardly or forwardly from the plane of the base or board so as to raise the free end of the indicator arm, whereupon the block may be slid parallel with the edge of 105 the base to the desired adjustment.

Also obviously the carrier block with its attachments including the indicator arm may be entirely removed from the base or board, when not required for indicating 110 lines of work disposed thereon, by disengaging the hook 23 of the retaining arm 22

from the holding rib 24. The carrier may be replaced with equal facility by disposing it adjacent to the edge of the base and snapping the hook 23 into engagement with the 5 rib 24.

What is claimed is:

1. A copy holder having a base provided with a pivotal easel support and means for limiting the deflection of the latter from the 10 plane of the base, said easel support having a transverse lower bar, and the base being provided with yielding buttons at its lower edge for engagement by said transverse bar when the easel support is folded.
- 15 2. A copy holder having a base and means for supporting the same in a substantially upright position, a clamp for securing copy upon the front surface of the base, front and rear guide ribs carried by the base 20 parallel with one side edge thereof, a carrier

block provided with front and rear spring arms for bearing contact respectively with said ribs, and a line indicator arm carried by said block.

3. A copy holder having a base and means 25 for supporting the same in a substantially upright position, front and rear guide ribs arranged parallel with one side edge of the base, a carrier block provided with yielding front and rear arms for bearing contact re- 30 spectively with said ribs, the rear arm having a terminal hook for engagement with the rear rib to prevent accidental displacement of the block, and a yielding line indicating arm carried by the said block and ex- 35 tends transversely of the surface of the base.

In testimony whereof he affixes his signature.

JAMES SHEEAN.
